(57) CLAIM

The ornamental design for a tank top with integrated bra, as shown and described.

DESCRIPTION

FIG. 1 is a front isometric view of a tank top with integrated bra, which embodies my design;

FIG. 2 is a back isometric view of the tank top with integrated bra;

FIG. 3 is a front view of the tank top with integrated bra;

FIG. 4 is a back view of the tank top with integrated bra;

FIG. 5 is a side view of the tank top with integrated bra;

FIG. 6 is a side view of the tank top with integrated bra;

FIG. 7 is a top plan view of the tank top with integrated bra;

FIG. 8 is a bottom plan view of the tank top with integrated bra;

FIG. 9 is an exploded view showing the interior of the tank top with integrated bra;

FIG. 10 is a front view in a position of use of the tank top with integrated bra; and,

FIG. 11 is a back view in a position of use of the tank top with integrated bra.

The broken lines in FIGS. 10 and 11 depict the human body and form no part of the claimed design.

The broken lines in FIGS. 2, 4, and 9 represent stitching which forms part of the claimed design.
